UNITED STATES PATENT OFFICE.

JAMES G. SMITH, OF COVINGTON, KENTUCKY, ASSIGNOR OF TWO-THIRDS TO
GEORGE HILDENBRANDT, OF SAME PLACE, AND GEORGE W. DAVY, OF
LOUISVILLE, KENTUCKY.

AUTOMATIC LUBRICATOR FOR JOURNAL-BOXES.

SPECIFICATION forming part of Letters Patent No. 634,860, dated October 10, 1899.

Application filed September 26, 1898. Serial No. 691,914. (No model.)

To all whom it may concern:

Be it known that I, JAMES G. SMITH, residing at Covington, in the county of Kenton and State of Kentucky, have invented certain new 5 and useful Improvements in Journal-Boxes and Lubricators, of which the following is a specification.

The object of my invention is to provide an automatic lubricator for journal-boxes. It 10 is specially adapted to be applied to the axles of cars and locomotives.

It is essential for the proper lubrication of journals that the lubricant shall be applied continuously. It is equally essential that the 15 supply shall be just sufficient and not in excess of the amount required for keeping the journal cool. All these and other objects are accomplished by my invention, the features of which will be more fully set forth in 20 the description of the accompanying drawings, which form a part of this specification, in which—

Figure 1 is a central vertical longitudinal section through the journal and lubricating 25 device. Fig. 2 is an enlarged cross-section on the line *x-x* of Fig. 1. Fig. 3 is an enlarged perspective view of the lubricating apparatus.

Referring to the drawings, the reference- 30 letter A designates the axle of a locomotive-truck; B, the journal-box; C, the brass bushing, and E the bolster supporting the box. D represents the box or cellar, which is suspended from the journal-box in the usual 35 manner.

F represents a shell frame or tray mounted upon springs G, which rest on the base of the oil-cellars, it being adapted to movably fit within said journal-box.

H represents a longitudinal saddle extending 40 transversely across said frame. This saddle is made of rigid material for reasons to be hereinafter set forth, and its opposite ends rest between and are supported by keepers H' 45 at the ends of the said tray, as shown in Figs. 1 and 3.

I represents a wicking or web of fibrous material adapted to take up oil by capillary attraction. This web is supported across 50 said saddle, and the lower ends thereof depend through longitudinal slots or openings a, formed in the bottom J of the tray F and

extend into the oil-cellars to convey oil in graduated quantities to the portion of the web extended over the saddle. In order that 55 there shall not be an excess of oil applied to the journal, the springs G are made strong, so as to press the web up against the axle with considerable force. The saddle H, being 60 of rigid material, acts to press or squeeze out 65 the surplus oil on each side of the contacting point of the web, and hence the journal is moistened with a very thin film of oil instead of a heavier coating, which would be the case if the saddle H were dispensed with, and 70 such surplus oil thus squeezed out finds its way back into the oil-cellars through the longitudinal slots a in the bottom of the tray.

At each end of the tray two vertical parallel walls are provided to form between them 75 narrow compartments, in each of which is detachably supported a dust-guard K, having a concave upper portion to closely fit the journal and prevent the entrance of dust or other foreign matter to the lubricating material. 75

By the construction herein described it will be obvious that the tray, dust-guards, and web are spring-controlled, and each is detachable from the journal-box, as well as from each other part, so that one part can be renewed or removed at any time independent 80 of the other.

I have found by experience that this form of lubricating device is simple, economical, and durable, effecting a saving of at least 85 fifty per cent. of the lubricant formerly consumed by previous devices. It is also a reliable automatic lubricator, adapted to be used in connection with all journal-boxes, supplying just the correct amount of lubricant and 90 avoiding any danger of overheating the journal-boxes.

Having thus described my invention, what I claim is—

A lubricating device for journal-boxes, 95 comprising an oil box or cellar, a removable spring-supported tray adapted to fit within said oil-box, a narrow compartment at each end of the tray formed by vertically-arranged parallel walls, and detachable dust-guards 100 supported in said compartments, the said tray being provided in its bottom with two longitudinal slots arranged parallel to each other and which extend throughout substan-

tially the whole length of the tray, a pair of separated lugs or keepers arranged within the tray at each end thereof, said lugs being carried by the inner vertical end walls of the tray, a longitudinal saddle of rigid material supported at its opposite ends between said lugs or keepers, said saddle being arranged between the longitudinal slots in the tray, and a fibrous web extending over the top of

said saddle and having its ends depending to through the said slots and lying in the oil box or cellar.

In testimony whereof I have hereunto set my hand.

JAMES G. SMITH.
